John W. Sharley,
Attorney

UNITED STATES PATENT OFFICE.

EDWARD W. LEECH, JR., OF BALTIMORE, MARYLAND.

SPRING OILER.

Application filed August 24, 1922. Serial No. 584,109.

To all whom it may concern:

Be it known that I, EDWARD W. LEECH, Jr., a citizen of the United States, residing at Baltimore, in the State of Maryland, have invented certain new and useful Improvements in Spring Oilers; and I do hereby declare the following to be a full, clear, and exact description of the invention, such as will enable others skilled in the art to 10 which it appertains to make and use the same.

My invention relates to spring oilers.

Among the objects of my invention are:—

15 To provide an oiler which can be readily applied to the ordinary leaf springs employed in vehicles.

To provide an oiler which can be readily removed from the spring for the purpose of cleaning and the insertion of new oil dispensing material.

To provide an oiler which can be readily refilled without removal from the leaf spring.

These and other objects of my invention will be explained in the following specification, reference being had to the accompanying drawings, and the means by which said objects are effectuated will be definitely pointed out in the claims.

20 In the drawings:—

Figure 1 is a side view of a leaf spring equipped with a pair of my improved oilers.

Fig. 2 is an enlarged section along the line 2—2 in Fig. 1 looking in the direction of the arrows.

Fig. 3 is a detail view of one of the oiling members shown in Fig. 2.

Fig. 4 is a view of the parts shown in Fig. 2 looking in the direction of the arrow 4 in said figure, the spring 10 being omitted.

Fig. 5 is a section along the line 5—5 in Fig. 3 looking in the direction of the arrows.

Fig. 6 is a view of my improved oiler looking in the direction of the arrow 6 in Fig. 2.

Fig. 7 is a section along the line 7—7 in Fig. 5 looking in the direction of the arrows.

Fig. 8 is a partial view of the upper projection viewed in the direction of the arrow 8 in Fig. 3.

50 In the drawings:—

10 is a spring having the usual plurality of leaves and 11 is the oiling member of my improved oiler which may be applied to either side of the spring 11 and is yieldingly held thereagainst as hereinafter explained.

The member 11 comprises a reservoir 12

for the oil 13 and the wick 14 is the means for distributing the oil from the reservoir 12 to the side of the spring 10.

A dust guard 15 is cemented or otherwise 60 secured around the opening in the reservoir 12 through which the wick 14 protrudes.

The reservoir 12 is provided with a screw hole closed by the screw 16 to provide means for introducing oil within the reservoir 12. 65 A lower projection 17 is formed integrally with the reservoir 12 and is provided with a nose 18. The upper projection 19 is hinged as at 20 to the reservoir 12 and is provided with a nose 21.

The projections 17 and 19 are provided with coupling surfaces 22 and 23, respectively, the former being at right angles to the upper surface of the projection 17 and the latter at an oblique angle to the lower surface of the projection 19.

The clamp 24 is provided with a hole 25 for the passage therethrough of the end 26 of the projection 17. Said clamp is also provided with a slot 27 for the reception of 80 the projection 19 and coupling surface 28 located to engage the coupling surface 23 on the projection 19.

In the clamp 24 there is threaded the adjusting screw 29 which serves to adjust the 85 spring 30.

The operation of my improved spring oiler is as follows:—

The screw 29 being turned backwardly as far as possible without disengagement from the clamp 24 and the latter not being in engagement with the projections 17 and 19, said projections are passed over the spring 10, the projection 19 being at the top thereof. The end 26 is then passed through the hole 25, the right end of the projection 19 is then lifted and the upper end of the clamp 24 is moved thereunder toward the left until the end 31 of the projection 19 will pass the outer edge of the surface 28. The projection 19 is then to be moved downwardly and the upper end of the clamp 24 moved toward the right to engage the surfaces 23 and 28. The screw 29 is then adjusted until the spring 30 produces the requisite amount of pressure upon the spring 10.

It is to be noted that the pressure of the spring 30 (see Fig. 2), presses the upper end of the clamp 24 toward the right, thus pressing the surface 28 upon the surface 23. A 110 part of this pressure results in a downward pressure of the nose 21 upon the spring 10.

and the reaction to this pressure is a pressure of the nose 18 upon said spring.

The reaction of the direct pressure of the spring 30 against the spring 10 is a pressure of the dust guard 15 against the spring 10.

Thus it will be seen that by the use of one spring I resiliently secure my improved oiler to the spring 10 and thus securely hold 10 my oiler in place with practically no increase of the friction between the leaves of the spring 10.

It is also to be noted that my improved oiler may be applied and removed without 15 the use of tools.

While I have shown one combination of elements for carrying out my invention, it is understood that this combination is exhibited for purposes of illustration only and 20 not in anywise to limit the scope of my invention, for many changes may be made in the structure shown without departing from the spirit thereof.

I claim:—

25 1. In a spring oiler, the combination with a leaf spring, of an oiling member mounted on one side thereof and comprising a reservoir for oil and means for distributing said oil to said spring, projections on said member extending across the top and bottom of said spring, and a clamp having sliding engagement with one projection and pressing against the other side of said spring and cooperating with said projections to press 30 said member against said first named side and to press said projections against the top and bottom of said spring.

2. In a spring oiler, the combination with a leaf spring, of an oiling member mounted 40 on one side thereof and comprising a reservoir for oil and means for distributing said oil to said spring, projections on said member extending across the top and bottom of said spring, and a clamp having sliding engagement with one projection and cooperating with said projections and the other side of said spring to press said member against said first named side and to press said projections against the top and 45 bottom of said spring.

3. In a spring oiler, the combination with a leaf spring, of an oiling member mounted on one side thereof and comprising a reservoir for oil and means for distributing said oil to said spring, projections on said member extending across the top and bottom of said spring, one of said projections comprising a flat surface, and a clamp comprising 55 a flat surface having sliding engagement with said first named flat surface and cooperating with said projections and the other side of said spring to press said member against said first named side and said 60 projections against the top and bottom of said spring.

4. In a spring oiler, the combination with a leaf spring, of an oiling member mounted on one side thereof and comprising a reservoir for oil and means for distributing said oil to said spring, projections on said member extending across the top and bottom of said spring, one of said members comprising a flat surface, and a clamp comprising a flat surface having sliding engagement with said first named surface, said clamp having engagement with the other of said projections and cooperating with the other side of said spring and said projections to press said member against said first named side and said projections against the top and bottom of said spring.

5. In a spring oiler, the combination with a leaf spring, of an oiling member mounted on one side thereof and comprising a reservoir for oil and means for distributing said oil to said spring, projections on said member, one of said projections being hinged to said member and comprising a flat surface, and a clamp engaging the other projection and comprising a flat surface engaging said first named surface for pressing said means against said spring.

6. In a spring oiler, the combination with a leaf spring, of an oiling member mounted on one side thereof and comprising a reservoir for oil and means for distributing said oil to said spring, projections on said member, one of said projections being hinged to said member and comprising a flat surface, and a clamp engaging the other projection and comprising a flat surface engaging said first named surface for pressing said means and hinged projection against said spring.

7. In a spring oiler, the combination with a leaf spring, of an oiling member mounted on one side thereof and comprising a reservoir for oil and means for distributing said oil to said spring, projections on said member, one of said projections being hinged to said member and comprising a flat surface, and a clamp engaging the other projection and comprising a flat surface engaging said first named surface for pressing said means and projections against said spring.

8. In a spring oiler, the combination with a leaf spring, of an oiling member mounted on one side thereof and comprising a reservoir for oil and means for distributing said oil to said spring, projections on said member, a clamp, a screw thread in said clamp and a spring pressed against said spring by said screw.

9. In a spring oiler, the combination with a leaf spring, of an oiling member comprising a reservoir for oil, means for distributing said oil to said spring, projections on said member extending across the top and bottom of said spring, coupling surfaces on said projections, a clamp engaging said surfaces and having sliding engagement

with one of said surfaces, and a spring mounted between said clamp and the other side of said leaf spring for pressing said member against said first named side and for pressing said clamp against said surfaces to press said projections against the top and bottom of said spring.

10. In a spring oiler, the combination with a leaf spring, of an oiling member mount-

ed on one side thereof and comprising a reservoir for oil and means for distributing said oil to said spring, projections on said member, noses on said projections and a clamp for forcing said noses against said spring.

In testimony whereof, I affix my signature.

EDWARD W. LEECH, Jr.
